DESIGN FOR A PHOTOGRAPHIC PROJECTOR

John A. Korengold, Chicago, Ill.

Application April 12, 1937, Serial No. 68,690

Term of patent 7 years

To all whom it may concern:

Be it known that I, John A. Korengold, a citizen of the United States, residing at the city of Chicago, county of Cook, State of Illinois, have invented a new, original, and ornamental Design for a Photographic Projector, of which the following is a specification, reference being made to the accompanying drawing forming a part

thereof, in which Figure 1 is a perspective view and Figure 2 is a rear elevational view of a photographic projector embodying my design.

I claim—

The ornamental design for a photographic projector, substantially as shown.

JOHN A. KORENGOLD.
